DUST EVACUATING DEVICE

Samuel Orr Hanna, Jamestown, N. Y.

Application September 15, 1937, Serial No. 164,023

4 Claims. (Cl. 51—273)

This invention relates to sanding devices and particularly to means for evacuating dust therefrom as it accumulates during a sanding operation.

Until comparatively recently it was not considered necessary, by the manufacturers at least, to provide means for collecting and evacuating dust as it was generated during the operation of a sanding machine. Some users of equipment of this nature provided their own fan evacuators because of the belief that the accumulated dust was injurious to the workmen and also seriously affected the working parts to all nearby machines. First attempts to collect and evacuate dust from sanding devices consisted in partially enclosing a pulley over which the sanding belt passed on leaving the work. These enclosures were not expected to remove any great portion of the dust since it was believed impossible to enclose a sanding device in such a manner as to leave only a small portion of the belt exposed and at the same time control the direction and movement of the dust from the belt as the belt was being applied to a given piece of work. Even with the provision of evacuating fans these enclosures were incapable of accumulating and evacuating more than a small portion of the dust created.

The present invention consists of a structure adapted to enclose certain parts of a sanding device for the purpose of collecting substantially all the dust created during operation thereof. The enclosure is so arranged that a desired directional movement of the dust is produced. Connecting the enclosure with an evacuating fan speeds removal of the dust but is not essential for the successful use of the invention.

One of the objects of the invention lies in the provision of means for collecting and removing dust as it is produced during the operation of a sanding device.

Another object of the invention lies in the provision of means for enclosing a pulley over which a sanding belt passes upon leaving a given piece of work.

Another object of the invention lies in the provision of means for enclosing all of the pulleys and a portion of the belt.

Another object of the invention lies in the provision of means for enclosing a sanding device which causes air currents generated by the pulley to withdraw dust from the belt and work as it is created.

Another object of the invention lies in the provision of means for enclosing all of a sanding belt with the exception of that portion necessarily

exposed for contact with a given piece of material.

Another object of the invention lies in the provision of means for enclosing a sanding device which is arranged to create initial air currents to withdraw dust, as created, from the belt and work and which may be coupled with power evacuating means.

Other and further objects and advantages of the invention will be more fully understood from a consideration of the following specification taken in conjunction with the accompanying drawing and in which

Fig. 1 is a front elevation of a sanding device embodying one form of the invention; 15

Fig. 2 is a vertical sectional view of a part of a structure embodying the invention, being taken substantially on the line 2—2 of Fig. 1;

Fig. 3 is a vertical sectional view of another portion of an enclosure for a sanding device, being taken substantially on the line 3—3 of Fig. 1; and

Fig. 4 is a perspective view of a pulley designed to create air currents within an enclosure for the purpose of evacuating dust. 25

Reference is now had to the drawing and particularly to Figure 1 wherein the numeral 10 is employed to generally indicate one form of sanding device to which the invention is applicable. The sanding device comprises a pair of spaced base members 11. Secured in any suitable manner to adjacent faces of the members 11 are tracks 12. Mounted on wheels 13 is a work table 14. The wheels 13 may be grooved for the purpose of better fitting the tracks 12. A handle 16 enables an operator of the device to move the table 14 for the purpose of locating any portion of a piece of material directly beneath the sanding belt. 30

The members 11 are continued upwardly and rigidly by a portion 17. Secured to the portion 17 is a track 18 on which is mounted a carriage 19 through sets of rollers 20. The carriage 19 supports a sanding or polishing member 21 which includes a housing 22 and a vertically movable member 23. Attached to the lower end of the member 23 is a shoe 24. 40

Adjacent the ends of portion 17, the uprights 11 are formed to provide ledges 26. These ledges are adapted to mount shelves 27. On the shelf 27 shown at the left of the drawing a motor is mounted which in turn supports a pulley 28. The shelf 27 at the right of the drawing is provided with a laterally movable portion which in turn mounts a further pulley 28 A. An endless 45

belt 29 is mounted on the pulleys and when it is desired to vary the tension of the belt, the pulley 28 A may be laterally adjusted for this purpose. It will be noted that the upper intermediate portion of the belt 29 is well above track 18 and carriage 19 and also that the lower intermediate portion of the belt lies beneath the shoe 24. When it is desired to sand a given piece of material located on the table 14, the table is moved over the tracks 12 to position the work beneath the belt 29 and shoe 24. A suitable operating lever serves to move the member 23 downwardly and cause shoe 24 to depress the moving belt 29 into contact with the material on the table. For the purpose of a clearer understanding of the invention and its operation it is assumed that the belt 29 is to be moved in the direction indicated by the arrow A.

The sanding device described is conventional in most respects and it is contemplated to enclose this or any other type of sanding device in such a manner that substantially all of the dust created during the sanding operation is withdrawn from the material, the sanding belt and the machine itself. In providing an enclosure that will satisfactorily serve this purpose it must be kept in mind that the enclosure must be so arranged as to properly utilize any air currents developed in the operation of the machine, and furthermore, must be of such structure as not to interfere with the proper operation of the device. With this in mind attention is directed to Figure 1 of the drawing wherein an enclosure is shown to comprise hoods 31 and 32. The hood 31 includes a rear wall 33 and a front wall 34 which is in the nature of a door, being provided with a hinge structure 35 for pivotally mounting it on a curved wall 36. Adjacent the upper part of the hood 31 the curved wall 36 is formed with an exhaust duct 37. It will be noted that the duct 37 is so located that it will readily take off any accumulated dust on the pulley 28 and belt 29 as said belt moves from off the material on the work table 14. The inner end of the hood 31 is closed by a vertical wall 38. This wall is the full width of the hood but is cut short adjacent the lower end to provide an opening 39. Through this opening the belt 29 passes as it leaves the work table. It will be noted that the belt is closely adjacent the lower edge of the wall 38 and that there is considerable space therebeneath. The opening 39 thus constitutes an air intake and if the suction is sufficient, dust on the abrasive surface of the belt, as well as any dust created on the material, will pass through this opening into the hood 31. To further aid in causing dust to enter the opening 39 it is to be remembered that the belt 29 is moving through this opening into the hood 31 and although the dust created may be at some distance from the opening, movement of the belt in that direction will cause said dust to flow along the belt into the opening and thence into the hood 31. The rear wall 33 is joined to the shelf 27 of the machine in any suitable manner as by bolts 41. These belts are provided with spacing sleeves 42 which locate the hood 31 slightly away from the machine bed and the driving motor.

The hood 32 is substantially identical with hood 31 already described, with the exception that the laterally adjustable pulley 28A necessitates slight elongation thereof. This hood is also formed with a door-like front wall 43 and a duct 44.

A further structure 46 is provided for the purpose of enclosing the upper central portion of the

belt 29. The enclosure 46 may, as shown in the drawing, be permanently joined to and serve to connect hoods 31 and 32, or it may be a separate unit removably attached to the hoods. It is to be noted that the walls 38 of hoods 31 and 32 stop short at the top wall of the hood and thereby provide end openings 47. The opening shown may be somewhat reduced in size by an angle plate 48 which serves to prevent part of the dust drawn into hood 31 from passing along the enclosure 46 into hood 32. The enclosure 46 comprises a base wall 49, top wall 51, and rear wall 52. The front of the enclosure is provided with a door 53 movable into open or closed position about hinges 54.

It has been found, under certain conditions of use, that dust gathers on the flanges of the pulley. To prevent such an accumulation of dust, as well as to create additional air currents, the inner surfaces of one or both pulleys may be provided with a series of blades 56 which are arranged not only to deflect dust therefrom but to create air currents and direct them toward the duct 37.

Having described the structural features of the invention, operation thereof is as follows. It is assumed that a piece of material 57 is placed on the table 14 and the table moved transversely of the machine to locate the material, or any given part thereof, directly beneath shoe 24. As the shoe is moved downwardly it engages the moving belt and causes it to contact with the material. Because the belt is moving in the direction indicated by the arrow A, air currents moving in that direction will be created and dust will follow these air currents along the belt, toward and into the opening 38 in hood 31. Due to the fact that the enclosures for the pulleys and belt are arranged to take advantage of and direct air currents generated during the operation of the device, it is possible in light sanding work to evacuate practically all of the dust without the aid of an evacuating fan and, under these circumstances, it will be understood that practically no dust passes through the enclosure 46 into hood 32, the entire accumulation of dust being taken care of by hood 31 and duct 37. Furthermore, in certain types of machines it is unnecessary to provide a hood for each of the pulleys and a connecting enclosure, such as the enclosure 46, one hood and duct being sufficient. However, in connection with heavy duty sanding, and also because of the high rate of speed at which sanding devices generally operate, it will be found advisable to connect ducts 37 and 44 with an evacuating fan. Under these conditions a part of the dust in the hood 31 cannot be passed out of duct 37 in the short time a given portion of the belt is traveling through the hood about pulley 28. Thus any dust remaining on the belt may become dislodged in the enclosure 46 from which it is carried into hood 32. As dust enters hood 32 it is withdrawn through duct 44.

It is to be understood that although the sanding belt has been considered to be moving in a direction indicated by the arrow A and hood 31 adapted to receive the belt and evacuate the greater part of any dust produced during a sanding operation through duct 37, the belt 29 may be made to travel in an opposite direction, and under such conditions, hood 32, which is substantially identical with hood 31, will receive and evacuate the greater part of the dust accumulated during the sanding operation. In other words,

the present invention has been designed to cover all practical conditions of use of a sanding device to which it is applicable.

Although applicant has shown and described only one modification of an enclosure for a sanding device by means of which it is possible to remove dust as created, it will be understood that other modifications or adaptations of the present structure for other types of sanding devices are contemplated and may be made insofar as these modifications or adaptations may be within the spirit and scope of the invention as defined in the hereunto annexed claims.

Having thus set forth my invention what I claim as new and for which I desire protection by Letters Patent is:

1. In a dust evacuating device for a sanding machine having a pair of pulleys and an endless belt thereon, comprising hoods enclosing said pulleys, said hoods having laterally inwardly directed openings adjacent the bottom thereof, and further inwardly directed openings adjacent the top thereof, said openings and said further openings serving to permit passage of said belt into and out of said hoods, and means enclosing only the upper portion of said belt between said hoods, said means being aligned with the further openings in said hoods.

2. In a dust evacuating device for a sanding machine having a work supporting table and a pair of pulleys adapted to mount an endless belt for movement over said table, said device comprising hoods enclosing said pulleys, means se-

curing said hoods to said machine, the adjacent walls of said hoods having top and bottom openings, means connecting said top openings, said means enclosing only the upper portion of said belt, a door on said means, a door on each of said hoods, the doors of said hoods and said means when open exposing the ends of said top and bottom openings to facilitate mounting and removal of said belt with respect to said pulleys.

3. In a dust evacuating device for a sanding machine having a work supporting table and a pair of pulleys adapted to mount an endless belt for movement over said pulleys, said device comprising hoods enclosing said pulleys, means securing said hoods to said machine, the adjacent walls of said hoods having top and bottom openings, a substantially channel-shaped member connecting said hoods and being aligned with said top openings, and a cover plate on said member and cooperating therewith to form an enclosure for the upper portion of said belt.

4. A dust evacuating device for a sanding machine having a pair of pulleys adapted to mount an endless belt thereon comprising hoods enclosing said pulleys, said hoods having laterally inwardly directed top and bottom openings, said openings serving to permit passage of said belt into and out of said hoods, means enclosing only the upper portion of said belt between said hoods, said means being aligned with the top openings of said hoods, and an exhaust duct connected with the interior of at least one of said hoods.

SAMUEL ORR HANNA.
